MELCHIOR ZWICKY, OF BERKSHIRE HEIGHTS, AND EMIL RICHTER, OF WYOMISSING, PENNSYLVANIA, ASSIGNEES TO TEXTILE MACHINE WORKS, OF WYOMISSING, PENNSYLVANIA, A CORPORATION OF PENNSYLVANIA.

DRIVE FOR FULL-FASHIONED-KNITTING MACHINES.

Application filed May 19, 1927, Serial No. 192,716. Renewed February 13, 1929.

The invention relates particularly to multiple section full-fashioned knitting machines, in which movements of like parts of each section of the machine are effected at required intervals through a common longitudinal cam shaft; the object in view being to practically eliminate objectionable effects of the torsional shaft strains commonly incident to such operation, and to advantageously care for the necessary strains with avoidance of vibrations and without objectionably affecting the general construction provided to meet the operating requirements of such machines.

Economies in construction and operation are obviously effected by employing a number of like sections combined in a single machine so as to simultaneously produce a corresponding number of like products such as full fashioned stockings. The resulting increased length of the machine however naturally calls particularly for increased strength in the longitudinal shafts through which the operations in the different sections are required to be simultaneously effected; and practicable variations in the construction of the machine are limited by the various functionings and general structural requirements. The present improvements provide in an advantageous way for minimizing the size and weight of the commonly required longitudinal shafts, and particularly of the cam shaft which has multiplied service put upon it and which is required also to be adjusted longitudinally for effecting certain of the operations; and this is accomplished essentially by the employment of a special torsion-taking countershaft advantageously mounted in the rigidly supported base portion of the machine so as to practically eliminate vibrations, as fully described in connection with the accompanying drawings, the novel construction being clearly defined in the subjoined claim.

Fig. 1 is a partly cross-sectional end elevation of a full fashioned knitting machine showing the frame structure and indicating my invention in connection with immediately cooperating parts commonly employed.

Fig. 2 is a diagrammatic view indicating the driving connections of the several shafts shown in Fig. 1.

Fig. 1 indicates only so much of the ordinary full fashioned knitting machine struc-

ture as sufficiently shows the usual relation of the commonly employed hand-wheel shaft C and the cam shaft D; both of which shafts extend the full length of the multiple-section machine as indicated in Fig. 2, so as to serve the several sections. The cam shaft D is provided at different portions of its length with required cams for the different sections, and is automatically adjusted lengthwise at intervals, as usual; while the hand-wheel shaft C enables hand control of the machine as required and at the same time overcomes irregularities of motion by its fly wheel effect. The shaft C is conveniently located for the operator at the front of the top portion of the machine, and is commonly driven by the motor and operatively geared to the cam shaft D.

The torsional strains on these shafts C and D, incident to the employment of numerous knitting sections in a single machine each with its intermittent cam actions, naturally calls for great torsional strength to insure satisfactorily uniform action in the different sections, and also causes very objectionable vibrations; and the manner of gearing them together is practically restricted by the requisite general construction of the machine with its complicated functionings.

I have found that the problem of insuring uniform cam action with minimum weight of these vitally operative long shafts C and D, and with practical elimination of objectionable vibrations, is satisfactorily solved by providing a special torsion-taking shaft E near the rigid base of the machine; this shaft E being readily made shorter than the shafts C and D, of any required cross-sectional strength, and rigidly mounted; and the gearing of it to the cam shaft D being so arranged as to distribute the operating strains for most effectively eliminating torsional as well as vibrating effects. In Fig. 2 the two parallel shafts C and D are indicated as extending the full length of the multiple section machine, while low-down parallel counter-shaft E is considerably shortened; the hand-wheel shaft C at the top of the machine being motor driven as usual, preferably through a centrally located drive gear F thereon, and having a closely adjacent gear G from which the low-down counter-shaft E is driven, a chain 10 being

employed to drive the latter as indicated in Fig. 2. The intermediate cam shaft D is geared to countershaft E by three pairs of gears H, H, H, which are widely spaced apart longitudinally of the shafts so as to evenly distribute the rotating action transmitted to the several lengthwise portions of the cam shaft D in accord with the work to be done by said portions. These several 10 driving connections between the shaft E and the vitally important cam shaft D, greatly reduce torsional effect upon the latter, and insure uniform cam action in all the sections even with comparatively light weight in the 15 shaft D; while the rigidly carried short shaft E, which may unobjectionably be made of ample cross-section, satisfactorily takes the torsional strains and prevents the objectionable vibrations which ordinarily occur. The convenience with which this low-down torsion-taking shaft may be satisfac-

torily applied to the essential machine structure is also of practical importance.

What we claim is:—

In a multiple section full fashioned knitting machine comprising a longitudinal cam shaft for all the sections and a parallel hand-wheel shaft therefor mounted above said cam shaft; a parallel torsion-taking counter-shaft mounted in the base portion of the 20 machine frame below said cam shaft, a motor drive-wheel and a take-off drive wheel for said countershaft adjacently mounted on said hand-wheel shaft, and a plurality of longitudinally-spaced driven gear connections between said countershaft and cam shaft.

In testimony whereof we affix our signatures.

MELCHIOR ZWICKY.
EMIL RICHTER.
